UNITED STATES PATENT OFFICE

LESTER C. BLACK, OF LOS ANGELES, CALIFORNIA

MULTISTAGE PUMP PLUNGER

Application filed January 24, 1928. Serial No. 248,997.

This invention relates to pump plungers which are adapted to be used in multi-stage pumps, and is an improvement on the multi-stage pump plunger as disclosed in my Patent No. 1,646,134.

One difficulty encountered in the actual operation of the plunger disclosed in the patent above referred to is the tendency for the comparatively sharp upper edges of the manganese steel cups to catch on the tubing between couplings, making it difficult to pull the plunger up thru the tubing.

In practically every type of deep well oil pump known it is customary to employ a very hard ball and seat valve. The tendency has always been to make these balls and seats of as hard a material as possible, in order to furnish the greatest amount of resistance against the tendency of sand, gas and water to cut them out. As positively demonstrated, it is impossible to construct a valve, operating under deep well conditions, of any material sufficiently hard to entirely resist the abrasive action encountered, and which will not eventually cut out.

In general, it is the object of my invention to provide a multi-stage pump plunger of a simplified construction and in which the sharp edges of the cup plungers, as disclosed in the patent above referred, have been eliminated, thereby overcoming the tendency of such plungers to engage with the walls and seams of the well tubing.

Another object of my invention is the provision of a cylindrical plunger provided with an apertured conical roof.

Another object of my invention is the provision of a valve seat constructed of a comparatively soft material upon which is contacted a valve base of a comparatively hard material.

My invention possesses other objects and features of advantage, some of which, with the foregoing, will be set forth in the following description of my invention. It is to be understood that I do not limit myself to the showing made by the said description as I may adopt various forms of my invention within the scope of the claims.

Referring to the drawings:

Fig. 1 is an elevational view of my improved multi-stage pump plunger in operative position within a pump barrel.

Fig. 2 is a vertical sectional view of my improved pump plunger showing the plungers in their closed position.

Fig. 3 is a vertical section of my pump plunger showing the plungers in their open position.

My invention contemplates the use of a plurality of identical pump sections 1. Although only one of said sections has been shown in the drawings, it is to be understood that any number of such sections may be used.

Each of these rod sections is provided with an enlarged head 2 at its upper end. This enlarged head is internally threaded as at 3 and is adapted to be threadedly connected to the threaded pin 4 of the adjacent section.

Carried in an annular recess on the upper face of the enlarged portion 2 is a valve seat 5 which is preferably constructed of a comparatively soft material such as bronze.

A shoulder 6 formed on the pin 1 engages the upper face of the valve seat 5 to hold the seat in place. The adjacent rod sections are further secured in place by means of a rivet 7 passing thru both the enlarged head 2 and the pin 4.

Loosely surrounding the rod section 1 is a cylindrical pump plunger 8 provided with contracted ends 9 and 11. The lower contracted end 11 is adapted to seat on the valve seat 5.

A plurality of radially disposed ports 12 is provided in the upper contracted end 9.

Formed on the lower end of the enlarged head 2 is an annular shoulder 13 which is adapted to limit the upward longitudinal movement of the plunger 8.

The plungers may be made of a comparatively hard material such as manganese steel and it is to be noted that the dimensions of the valve seat 5 are such as to insure the proper seating of the contacting area of the valve formed at the lower contracted end 11.

The uppermost section 1 is provided with wrench faces 14 and 15 and its upper end is provided with a threaded pin 16 to which the sucker rod (not shown) may be secured. It is thought

that the operation of the device is apparent from the above disclosure and that it therefore needs no further explanation.

This type of cup or plunger not only eliminates the necessity of a guide as disclosed in my Patent No. 1,646,134 or shroud as disclosed in my co-pending application, Serial Number 248,998 filed on January 24, 1928, but also permits of a much more simplified design of pump skeleton, as the upper portion of the cup or plunger is allowed to contact with the shoulder provided on the lower part of the enlarged head 2 thereby limiting the longitudinal travel of the cups or plungers. The upper reduced portion of the plungers also functions as guides to limit their lateral movement with respect to the plunger rod always retaining them in a concentric position in relation thereto. By such a construction the necessity of milling slots in the plunger rod or skeleton to act as oil ports is eliminated. All that is necessary in this type of construction to provide a passage for the fluid when the plunger is in the upper or down stroke position, is to turn the lower section of the plunger rod to a smaller diameter as is clearly shown in the drawings, thereby increasing the openings between the inside diameter of the lower portion of the cup and the outside diameter of the skeleton or plunger rod at the point desired. Such a construction is far more economical than any multi-stage pump plunger now on the market.

35 The theory of operation of the valve used in my device is as follows. Knowing that any type of valve seat employed will eventually be scored or cut, a valve has been provided which will hammer or pean out these minor cuts or abrasions as rapidly as they occur. For example, assuming that a grain of sand should lodge between the lower reduced portion of the plunger and its seat, the closing operation of the valve would cause the valve seat to be cut by the sand. The next pump cycle will cause the valve to strike or press down on the seat and if the seat is constructed of a sufficiently soft material the minor cuts caused by the preceding stroke will be closed up or peaned out by the blow and pressure of the plunger on the valve seat. This action has been successfully demonstrated in actual field tests and has proven entirely practical.

55 I claim:

1. A multi-stage pump plunger comprising a plunger rod; a plurality of spaced enlarged portions provided on said rod; a valve seat on the upper end of each enlarged portion and an annular shoulder on the lower end of each enlarged portion; cylindrical plungers having ends of a reduced diameter loosely surrounding said rod and longitudinally slid able between adjacent enlarged portions, the reduced upper ends of said

plungers having a plurality of ports, the cylindrical plungers being gradually merged into the ends of reduced diameter in the form of a continuously curved surface whereby to eliminate the formation of protuberant edges which would tend to catch on the joints of the pump tubing. 70

2. A device of the class described comprising a rod formed of a plurality of identical sections, each section having a valve seat 75 formed adjacent its upper end and an annular shoulder beneath said valve seat, and a cylindrical plunger having contracted ends loosely surrounding each rod section and longitudinally slid able between the valve seat 80 of one section and the annular shoulder of the adjacent section, the cylindrical plungers merging into the contracted ends thereof in a continuously curved surface so as to eliminate the formation of protuberant edges 85 which would tend to catch on the joints of the pump tubing.

3. A device of the class described comprising, a plunger rod, a valve seat carried by the rod, a cylindrical plunger circumferentially contacting the pump tubing and having gradually contracted ends loosely slid able on the plunger rod, the said plunger cooperating at its lower end with the valve seat, and having an apertured conical roof, the cylindrical plungers merging into the contracted ends thereof in a continuously curved surface so as to eliminate the formation of protuberant edges which would tend to catch on the joints of the pump tubing. 90

4. A multi-stage pump plunger comprising, a plunger rod, a plurality of spaced valve seats carried by said rod, a cylindrical plunger cooperating with each valve seat and circumferentially contacting the pump tubing, each plunger having gradually contracted ends loosely surrounding the said rod and being slid able thereon, and cooperating at the lower end thereof with its respective valve seat, each plunger having an apertured conical roof, the cylindrical plungers merging into the contracted ends thereof in a continuously curved surface so as to eliminate the formation of protuberant edges which would tend to catch on the joints of the pump tubing. 95

5. A pump plunger comprising, a plunger rod, a valve seat carried by the rod, an annular shoulder on the rod spaced from the valve seat, a cylindrical plunger circumferentially contacting the pump tubing and having gradually contracted ends loosely surrounding the rod, the plunger being adapted to slide on the rod between the seat and shoulder and cooperating at its lower end 100 with the valve seat, the plunger being formed with an apertured conical roof, the cylindrical plungers merging into the contracted ends thereof in a continuously curved surface so as to eliminate the formation of protuberant edges which would tend to catch on the joints of the pump tubing. 110

120

tuberous edges which would tend to catch on the joints of the pump tubing.

6. In a pump plunger, a plunger rod, a valve seat carried by said plunger rod and composed of malleable metal, and a cylindrical plunger loosely surrounding said rod and mounted for reciprocating movement relative to the rod during operation, one end of said plunger being composed of a relatively hard metal and adapted to forcibly impact against said valve seat on one of the strokes of said plunger, whereby said valve seat is reconditioned by the blows imparted thereto by said plunger.

15 In testimony whereof, I have hereunto set my hand.

LESTER C. BLACK.
